C. A. SPEASL.
INTERNAL COMBUSTION ENGINE.
APPLICATION FILED FEB. 8, 1918.

1,282,482.

Patented Oct. 22, 1918.

UNITED STATES PATENT OFFICE.

GEORGE A. SPEASL, OF NEWTON, ILLINOIS, ASSIGNOR OF THREE-TENTHS TO GEORGE KINSEL, ONE-TENTH TO H. W. BREITZMAN, ONE-TENTH TO W. H. PIPPIN, ONE TWENTIETH TO C. J. MUSGROVE, AND ONE-TWENTIETH TO A. J. KINSEL, ALL OF NEWTON, ILLINOIS.

INTERNAL-COMBUSTION ENGINE.

1,282,482.

Specification of Letters Patent.

Patented Oct. 22, 1918.

Application filed February 8, 1918. Serial No. 216,026.

To all whom it may concern:

Be it known that I, GEORGE A. SPEASL, a citizen of the United States, residing at Newton, in the county of Jasper and State 5 of Illinois, have invented certain new and useful Improvements in Internal-Combustion Engines, of which the following is specification.

This invention relates to internal combustion engines of the opposing cylinder type, 10 and has for its special object to improve the driving connections between the several pistons of various multiples of the two opposed cylinder units.

15 In engines of this kind, as heretofore constructed, there has been an objectionable tendency to excessive friction between the pistons and the sides of the cylinders on account of the lateral thrust of the crank to 20 which the piston rods are connected, and it is the aim of this invention to overcome this side draft or thrust of the pistons, thereby decreasing friction and side slap and insuring long wear and more power.

25 The invention will be first hereinafter described in connection with the accompanying drawings, which constitute part of this specification, and then more specifically defined in the claims at the end of the description.

30 In the accompanying drawings, wherein similar reference characters are used to designate corresponding parts throughout the several views—

35 Figure 1 is a broken plan view of an engine composed of four of the opposed-cylinder units, two above and two below in tandem fashion, the upper cylinders being removed, however, in this figure to more 40 clearly illustrate the driving connections.

45 Fig. 2 is a side elevation of two superposed opposed-cylinder units with the driving connections therefor.

Fig. 3 is a longitudinal section on the line 3—3 of Fig. 1, including the upper pair of cylinders; and

Fig. 4 is a cross section on the line 4—4 of Fig. 1.

50 The engine is preferably composed of two, four or some other multiple of two opposed cylinder units, four of such units being illustrated in the drawings by way of illustration. Said units are arranged tandem

fashion in pairs, each pair having one unit superposed upon the other. Thus, in Fig. 2, one unit, consisting of the opposed cylinders 1 and 2, is superposed upon another unit consisting of opposed cylinders 3 and 4, and, as suggested in Fig. 1, other pairs of similar units may be added and connected 60 up with the same driving means, the upper cylinders of the added pair of units being designated 5 and 6 in this figure. The cylinders of each unit are connected by a tubular member 7 which serves as a guide for the 65 double piston 8 and which has an axially extending slot 9 for the working of the bent end portion 10 of the piston pin or arm 11 carried by a longitudinal guide rod or slide 12 working in ways formed in connecting 70 straps or ears 13 of the cylinder casting.

The crank shaft 14 passes between the upper and lower units of each pair and is arranged transversely midway of the cylinder coupling member 7. The guide rod or 75 slide 12 is preferably formed with a loop 15 to work around the crank shaft; and the piston pin or arm 11 for the upper unit is connected to the upper portion of said loop while the corresponding arm 16 for the 80 lower unit is connected to the lower portion of said loop, as illustrated in Fig. 4. The bent end portion 10 of the arm 11 extends upwardly for connection with the double piston 8 of the upper unit, while the corresponding bent end portion 17 of the arm 16 extends downwardly for connection with the double piston 8 of the lower unit. It will thus be seen that the double pistons in 85 both units move together in the same direction.

The impulses of the pistons, which are transmitted directly to the guide rod 12 through the piston pins or arms 11 and 16, are communicated to the crank shaft 14 by 95 a connecting rod or pitman 18 swiveled at one end to the crank 19 on said shaft and at the other end to a pin 20 on said guide rod. Each of the four cylinders 1, 2, 3 and 4 of each tandem pair of units is adapted 100 to fire in turn, exhaust in turn, charge in turn and compress in turn, and this cycle of operations takes place in rotation in the several cylinders. Thus, when cylinder 1 is fired and its piston is making the power 105 stroke, the charge is being compressed in

cylinder 2, the charge is being taken into cylinder 3 and cylinder 4 is being exhausted. It will be understood that the engine is of the four cycle type and that any suitable 5 valve system may be used with it.

When another pair of units is used, as suggested in Fig. 1, the crank shaft 27 thereof is arranged in line with the crank shaft 14, and the crank 28 on the shaft 27 10 is connected to the pitman 18 in line with its connection to the crank 19, so that the cycle of operations in the cylinders of the second pair of units will be the same as in the first pair.

15 The crank shaft need have only two main bearings and one connecting rod bearing, requiring a very small and light fly wheel, so that the device is easy and inexpensive to construct. The pistons are made extra long 20 while the stroke thereof is short, thus insuring long wear and great power. The long guide rod or slide 12 also reduces friction and increases the power of the engine, because the crank in all positions will be at 25 only a slight angle to said slide, and the side pressure of the pistons against the walls of the cylinders will, consequently, be reduced to a minimum. The piston pins or 30 arms 11 and 16 are made of select steel and are flattened so as to give them great strength in the direction of travel of the pistons. By reason of the few moving parts, less material and labor is required to manufacture this invention than previous devices 35 of this type, and less expense is required for its upkeep and lubrication. At the same time this improved engine will develop the

maximum horse power and is of superior flexibility.

While the invention is herein shown and 40 described as used in an internal combustion engine it will be readily understood that such use is not limited to engines of that character but that the invention is equally applicable to steam, compressed air or similar 45 type of engine.

Having thus fully described my invention, what I claim as new and desire to secure by Letters Patent of the United States, is—

1. In an engine, the combination with two 50 pairs of opposed cylinders arranged in parallel, of double pistons each having its opposite end portions arranged in the cylinders of one pair, a slide guided to move axially of said cylinders and having a loop, 55 arms carried by the opposite portions of said loop and connected respectively to the intermediate portions of the double pistons, a crank shaft extending through said loop, and driving connection between said slide 60 and crank shaft.

2. In an engine, the combination with two pairs of opposed cylinders arranged in parallel, of double pistons each having its opposite end portions arranged in the cylinders of one pair, a slide guided to move axially of said cylinders and having a loop, 65 arms on said slide connected respectively to the intermediate portions of the double pistons, a crank shaft extending through said loop, and driving connection between 70 said slide and crank shaft.

GEORGE A. SPEASL.
